(57) **CLAIM**

The ornamental design for a spoon rest, as shown and described.

DESCRIPTION

FIG. 1 is a top perspective view of a spoon rest showing our new design, the broken lines are for illustrative purposes only and form no part of the claimed design;

FIG. 2 is a top plan view thereof;

FIG. 3 is an end view thereof;

FIG. 4 is an opposite end view thereof;

FIG. 5 is a side view thereof, the opposite side view being the same;

FIG. 6 is a bottom plan view thereof;

FIG. 7 is a perspective view of a second embodiment the difference being the surface decal; the broken lines in FIG. 7 show an example of an image, which forms no part of the claimed design; and,

FIG. 8 is a partial section view taken along line 8—8 of FIG. 7, illustrating that the decalomania decoration forms an integral layer, which conforms to the top surface of a ceramic substrate with an example of the image of the decoration oriented to face upward so that the decoration is visible from the top.

The third embodiment, not shown, is the same as that shown in FIGS. 1—5 with no bottom view being claimed.

The fourth embodiment, not shown, is the same as that shown in FIGS. 7 and 8 with no bottom view being claimed.
